Inventor:

Thomas M. Rees.
By A. C. Johnston,
his attorney.

UNITED STATES PATENT OFFICE.

THOMAS M. REES, OF PITTSBURG, PENNSYLVANIA.

RE-ENFORCING THE HULLS OF VESSELS.

SPECIFICATION forming part of Letters Patent No. 388,917, dated September 4, 1888.

Application filed October 21, 1887. Serial No. 253,041. (No model.)

To all whom it may concern:

Be it known that I, THOMAS M. REES, of Pittsburgh, in the county of Allegheny and State of Pennsylvania, have invented a new 5 and useful Improvement in Constructing the Hulls of Vessels; and I do hereby declare the following to be a full, clear, and exact description thereof.

My invention relates to improvements in 10 the art of constructing the hulls of vessels of iron and steel; and it consists in the improved method hereinafter described, and pointed out in the claims.

To enable others skilled in the art with 15 which my invention is most nearly connected to make and use it, I will proceed to describe its construction and operation.

In the accompanying drawings, which form part of my specification, Figure 1 is a section 20 of the bow-stem of a vessel. Fig. 2 is an iron or steel plate cut in the form for securing to the bow-stem. Fig. 3 is a section of the bow of a boat representing said plate secured to the bow-stem. Figs. 4 5 6 represent sections 25 of the same at lines *a b c* of Fig. 2. Fig. 7 is a modified form of the plate shown in Fig. 2.

The bow-stem *A* is constructed in the usual manner and of any desired contour, and is provided with the necessary openings *B* for rivets. 30 In the bow-stem is formed a transverse slot, *C*, inclined inward and forward, as shown in Fig. 1. The stem-plate *D*, Fig. 2, made of iron or steel, is formed with bifurcated extensions *e* connected together by the main or butt end *E* of said plate. Into the slot *C* in the stem is 35 inserted the central portion of the butt end *E* of the plate *D*, the extensions *e e* of which straddle the bow-stem forward of the slot *C*, the edges *ff* of the plate *D* being flanged down and riveted to the bow-stem, as indicated in Figs. 3 and 4.

The part of the plate *g* between the dotted lines in Fig. 2 is secured to the bow-stem *A* by means of screw-bolts, as indicated in Figs. 3, 5, and 6. In all 40 other respects the hull of the vessel is constructed in the usual way. It may be of advantage to construct the plate *D* in three

pieces and rivet them together, as shown in Fig. 7.

The essential feature of my invention is the 5c employment of the slot *C* and inserting in it that portion of the plate *D* between the dotted lines in Fig. 2, and flanging down the edges *ff* of said plate and securing it to the bow-stem in the manner indicated in Figs. 3, 4, 5, 6. 55

The advantage of my invention will be apparent to the skillful ship-builder without further description.

Having thus described my improvement, 60 what I claim is—

1. As an improvement in the art of constructing the hulls of vessels of iron or steel, the method hereinbefore described, to wit: first, forming a slot in the bow stem, and, second, forming the bow-plate to straddle said 65 stem and rest in said slot, substantially as described.

2. As an improvement in the art of constructing the hulls of vessels of iron or steel, the method hereinbefore described, consisting of forming in the bow-stem a transverse slot inclined inward and forward, and then inserting and securing in said slot the butt-end of the stem-plate, so that the bifurcated extension, of said plate extend forward, 75 substantially as described.

3. As an improvement in the art of constructing the hulls of vessels of iron or steel, the method hereinbefore described, consisting of, first, forming in the bow-stem a transverse 80 slot inclined inward and forward; second, inserting and securing in said slot the central part of the butt-end of the stem-plate with the bifurcated extensions thereof reaching forward, and, third, flanging down and riveting said extensions to the stem, all substantially as described.

In testimony whereof I have hereunto set my hand this 12th day of October, A. D. 1887.

THOMAS M. REES.
